MARKING MACHINE

Charles E. Edwards, Beverly, Mass., assignor to
United Shoe Machinery Corporation, Borough
of Flemington, N. J., a corporation of New
Jersey

Application May 17, 1937, Serial No. 142,940

20 Claims. (Cl. 101—21)

This invention relates to marking machines and is herein illustrated as embodied in a machine, of the type employing both type disks and interchangeable type pieces, such as is extensively employed in shoe factories, for example, for marking sizes and lot numbers on the loose parts which are to be assembled to form a complete shoe. In this sort of a machine, the work is laid on a work-supporting table and the mark is applied by a head which is oscillated into contact with the work by power supplied through a pitman.

Pieces of work which are presented to such a machine are of varying character, being sometimes made of textile material and at other times of upper leather. Such leather for shoe uppers may vary radically in thickness between the thin, light kids which are employed in women's shoes and the heavy scotch grain or Cordovan leathers which are employed in men's shoes. Uniform marking on materials of such varying characteristics has not been easily obtained. Furthermore, where the marking members are heated, it is frequently desired to be able to vary the dwell of the members on the work and usually this could not be accomplished without at the same time causing a substantial variation in the pressure applied.

Accordingly, one important object of the invention is to provide an improved machine having flexible operating characteristics such that it is possible to vary the dwell of the members on the work without substantial change in the applied pressure.

35. This object is accomplished, in accordance with a feature of the invention, by the provision of an adjustably fixed work support together with an operating pitman for the oscillatable marking head, which pitman has a slidable connection to one of the parts to which it is connected and embodies yielding pressure-transmitting members or springs, the tension of which may be readily changed by an associated adjusting means.

Still another object of the invention is to provide a machine, utilizing both type disks and loose type pieces, in which the interchange of type pieces is greatly facilitated and in which the wear on the parts is lessened.

This object is realized, in accordance with other features of the invention, by an improved construction of a supporting member for the auxiliary type pieces, the construction of the pieces themselves, a preheater designed to maintain the pieces at operating temperature, by the construction of operating and detent pawls which are as-

sociated with the type disks, and by improved means for applying heat to the type disks.

These and other features of the invention will best be understood from a consideration of the following description, taken in connection with the accompanying drawings, in which

Fig. 1 is an angular view, showing the machine as a whole;

Fig. 2 is an angular view of a preheater for the loose type pieces;

Fig. 3 is a vertical, front-to-back section through the head of the machine, showing a supporting member for the loose type pieces in depressed position;

Fig. 4 is a bottom view of the head of the machine;

Fig. 5 is a rear elevation of the marking head detached from its hanger;

Fig. 6 is a view on a reduced scale of the yielding pitman between the crank shaft and the walking beam;

Fig. 7 is a fragmentary angular view of a portion of a type disk, showing an operating pawl associated therewith, in its released position, and

Fig. 8 is an angular view of the type disk viewed from a different direction and showing associated therewith a detent for holding it against rotation, the latter being in its operative position with respect to the type disk.

This machine is of the type shown in Letters 30 Patent of the United States No. 960,029, granted May 31, 1910, on the application of F. W. Merrick, and, as in that machine, pieces of work laid

on a work table 10 are printed by type members carried on a marking head 12. This is supported 35 for up-and-down movement toward and away from the work table by means of a hanger 14 suspended by means of pointed screws from the forward arm of a walking beam 16 which is pivotally supported between side members 18 and 20 40 of a frame 22. The marking head 12 is always held in a substantially vertical position during its up-and-down movement, being guided by a pivoted arm 24 as oscillations are imparted to the walking beam 16 by means of a pitman 26 at- 45 tached to a crank 12 (Fig. 6) on the crank shaft 28. This shaft is connected by gears 30 to a drive shaft 32 which is provided with a pulley (not shown) to which power is supplied to operate the machine. Control of the machine is effected by a clutch mechanism 34, connected to a treadle through a rod 36, so that the machine may be operated through one or more cycles while the treadle is depressed and will be 50

55

always stopped in the same position when the treadle is released.

The cycle of operation of the machine is such that the marking head 12 is raised slightly thereby permitting ink to be applied to the type members from a ribbon 40 positioned above a pad 42 which is carried on a pad arm 44 extending forwardly from a cross rod 46. The arm is joined to the hanger 14 by an arm 45 (Fig. 3) having an adjustable eccentric pivot stud 47. The marking head then descends and the pad arm 44 is moved downwardly to the rear as the type members are brought into contact with the work and then raised to bring the head to its stop position, substantially as shown in Fig. 1. The inking ribbon 40 passes over a roller (not shown) at the forward end of the arm 44 and beneath a curved guard 48, by which accidental contact with the work or the operator's hands is avoided.

The ribbon 40 extends between an upper spool 49 and a lower spool (not shown), the arrangement being such that the ribbon is moved forward step by step at each oscillation of the arm 44 by mechanism shown and described completely in Letters Patent of the United States No. 2,111,556, granted March 22, 1938, upon an application filed in the name of R. A. Crosby for improvements in Marking machines.

The work support 10 having a resilient pad 50 is supported on a vertical plate 52 which has removable side plates 54 forming guides which cooperate with vertical ribs at the sides of the end of a horizontal arm 56. This arm is pivoted at the rear of the side members 18 and 20 and may be adjusted with respect to the base of the frame 22 by means of a supporting screw 58 to bring the work support into parallelism with the marking characters on the head 12. Adjustment of the work support 10 vertically with respect to this arm 56 is effected by means of a hand wheel 60 having a threaded stem 62 coaxing with a lug 64 on the forward end of the arm 56.

The pitman 26 has an upper crosshead 66 (Fig. 6) pivoted on the rear arm of the walking beam 16 and a lower crosshead 68 pivoted at 70 on the crank 72. These upper and lower crossheads 66 and 68 are joined by parallel rods 74 firmly secured to the lower crosshead 68 and provided with nuts forming heads 76 which limit the upward movement of the upper crosshead 66 and therefore determine the length of the pitman. Surrounding the rods 74 are helical springs 78, one on each rod, the upper ends of which abut the lower side of the crosshead 66 and the lower ends of which abut a slide block 80 mounted on the rods 74 and adjustable in position with respect to the lower crosshead 68 by means of a screw 82 which is threaded in the block 80 and which has a head 84 provided with sockets to receive a pin or a spanner wrench. Inasmuch as the length of the pitman is determined by the heads 76 at the upper ends of the side rods 74, the path of movement of the marking head remains unchanged regardless of the adjustment of the spring tension. It is then possible, with a single piece of work on the work support, to vary the dwell or interval during which the marking members stay in contact with the work, by raising or lowering the work support by means of the hand screw 60. In addition, moreover, it is possible by adjusting the tension of the relatively light springs 78 to enable the machine to be used for stacked work in which a dozen or fifteen pieces are placed under the marking head and then are removed one by one, for example, allowing each

top piece of the stack to be printed. Under such conditions, the marking position may vary vertically as much as an inch but the change in the compression of the springs 78 corresponding to this variation is so small compared with the total pressure which the springs normally exert that the printed impressions are made with great uniformity.

Turning, then, to the marking head 12, it will be seen that this comprises a frame having a top plate 86 (Fig. 5), through which pass screws to attach the head to the hanger 14, and side plates 88 and 90, between which extend both a bracing member 92 and hollow sleeves 94 and 96 arranged to rotate together by reason of a key 98. The inner of these sleeves is integral with a pinion 100 meshing with another pinion 102 to which there is attached a heat-insulated hand wheel 104 (Fig. 1). Type disks 106, 108, 110, etc., are rotatable on this outer sleeve 94, being frictionally engaged therewith so that the turning of the sleeve effects the turning of such type disks as have been released from the finger-operated, spring-pressed, pivoted detents, the handles 114 of which are shown in Fig. 1. For the sake of simplicity of illustration, only three of these type disks have been shown in Figs. 4 and 5, and the remaining space has been filled by means of spacing sleeves 116, the length of which depends on the number of type disks employed, the whole assemblage being held together by means of lock nuts 118. Heat is transmitted to the type disks from a specially constructed heating cartridge 120, the winding of which is so arranged that there are fewer turns at the central portion thereof than at the end portions. This construction is desirable for the reason that the type disks at the end lose heat faster by conduction through the metal of the head 86 than do those at the center of the head. The cartridge is held in position by a clamp 121 which is screwed to the side frame 90.

The particular type disks 106, 108 and 110 are those which are employed for the purpose of marking the sizes and half sizes on shoes, the digits on the type disks 106 and 108 running from 0 and 1 to 9. These peripheral printing characters 122 are engraved on the ends of the teeth of the type disk in the usual fashion and in the recesses between the teeth are engraved indicating characters 124 which, when observed by the operator at the front of the marking head, indicate the particular printing character 122 which is in marking position at the bottom of the type disk. Inasmuch as the type disk 108 is the one which needs to be changed most frequently and since the run of sizes will ordinarily include half sizes, the type disks 108 and 110 have been arranged for operation together in the general manner described in Letters Patent of the United States No. 980,588, granted February 21, 1911, on an application of F. W. Merrick, but differing therefrom in details. The general arrangement is such that by oscillating a handle 126 from front to back through a short arc, the two disks 108 and 110 may be moved to provide at each oscillation a full-size number, such as size 4, and then a half-size number, such as size 4½, and then the next full-size number, such as size 5. This handle 126 is attached to a thin plate 128 (Fig. 3) which surrounds the sleeve 84 immediately beside the half-size disk 110 and which has pivotally attached to it a pawl 130 provided with a tooth 132 for engagement between two of the projecting teeth on the half-size disk 110. This

pawl is pivoted to the plate 128 at 134 and is provided with an open-slotted portion 136 which coacts with a reduced section of a washer 137 on the cross rod 138 on which the hub 139 of the above-mentioned detents (attached to the handles 114) are mounted. The position of the pawl 130 with respect to the plate 128 is determined by means of a locking screw 140 (Fig. 5) which is threaded into the pawl and which passes through a slot 142 in the plate 128. By means of this locking screw, the pawl may be thrown temporarily into inoperative position permitting a change in the teeth of the half size disk 110 to be engaged by the pawl tooth 132 so that the character used to indicate the half-sizes may be either the figure "1/2" or the figure "5", or some other symbol which the shoe manufacturer wishes to use. Having selected the desired character, the pawl is dropped into operative position, as shown in Fig. 3, and locked there by means of the screw 140.

On opposite sides of the size disk 108 are thin plates 143 and 144, each of which has ratchet teeth, these plates being secured to the type disk 108 by means of rivets 146. The teeth of these ratchet plates are radially aligned with the teeth of the disk 108. Backward rotation of the type disk 108 is prevented by means of a special detent 150 pivoted on the rod 138 and having an end portion 152 which is held against the teeth of the ratchet plate 144 by means of a coiled spring 154 which rests against a corrugated rod 156 (Fig. 5) extending transversely of the head to receive this and the other springs cooperating with the detents whose handles have been shown at 114. The detent 150 is made shorter than the other detents and has no handle because it is desired to have the movement of the size disk 108 progressive in a single direction. In previous constructions, this detent 150 has cooperated with the toothed periphery of the type disk and, consequently, has dragged over the engraved characters 122 thereon, thereby wearing these characters unduly. In the present instance, the end 152 of the detent drags over the teeth on the thin plate 144, which may be hardened if desired, and does not rub on the engraved characters at all. To prevent lateral displacement of the end 152 with respect to the thin ratchet plate 144, the lower end 152 of the detent has a cross stud 158, an enlarged portion 160 of which is provided with a terminal flange 162 which cooperates with the opposite side face of the type disk 108 to hold the end of the detent in alignment with the ratchet plate 144. The design and dimensions of the ratchet plate 144 are such, however, that the enlarged portion 160 of this stud can never contact with the engraved characters 122 but will be raised above those characters as the size disk is rotated.

To effect a step-by-step rotation of the size disk 108, an operating pawl 164 has been provided which is pivotally mounted on the lower end of the thin plate 128 by means of a screw stud 166, this stud being held in position by means of a nut 168 (Fig. 5). Surrounding the stud 166 is a coiled spring 169, one arm of which rests on a bar 170, which passes through a slot in the plate 128 and is secured to the outer end of the pawl 164, and the other arm of which is bent at 172 (Figs. 3 and 7) to be hooked into an opening 174 (Fig. 3) in the plate 128. The end of the pawl 164 cooperates with the ratchet plate 143 and is held in alignment therewith by means of a stud 174 having a flanged end por-

tion 176 which overlaps the periphery of the size disk 108 and coacts with the other face thereof. If, then, the handle 126, shown in Fig. 3, is pulled to the right, as viewed in that figure, the pawl 164 will engage the radial face of one of the teeth on the ratchet plate 143 and cause a clockwise rotation of the size disk 108 with the half-size disk 110. During this movement, the detent 150 will ride over the inclined surface of the ratchet plate 144 (Fig. 3) and fall into the next notch of that plate so that when the reverse oscillation of the handle 126 is effected, the detent 150 will hold the size disk and allow the operating pawl 164 to ride over the next tooth of the ratchet plate 143 on the other side of the size disk preparatory to the next reverse oscillation and, hence, forward movement of the type disk. It will be understood that the half-size disk is moved back and forth with each movement of the handle 126 and that, in one position, it will print a character such as the number "1/2" while, in the other position, it will not print at all.

Since it frequently is desired to do three-line marking, the head is provided with a plate 180 extending transversely thereof at the rear side and provided with a cartridge heating unit 182. Leads from this and the unit 120 are carried through a junction box 184 attached by screws to the side of the head and, thence, through a cable 186 (Fig. 1) to a switch box 188 having a pilot light 190 and a switch 192. The plate 180 is provided with a groove 194 extending lengthwise of the head for the reception of the rear edge of a name plate 196 having engraved thereon the trade-mark 198 of a particular manufacturer or any other suitable and desired legend. The upper surface of this plate is grooved at 200 to receive the head of a stud 202 (Figs. 3 and 4) and is held in position by means of a pivoted latch plate 204. The thin end portions 206 of this plate are received beneath a small bracket 208 screwed to the side of the head. It will be observed that the characters 198 are at exactly the level of the characters 122 on the type disks. The separate heating of this type plate through the unit 182 greatly facilitates the production of a uniform mark on the work.

Still another row of characters may be printed at the same time by means of loose type pieces 210, each of which is provided with a rectangular notch 212 for engagement with a crossbar 214 of polygonal cross section extending transversely of the head on a slidable frame which is made up of side rods 216 and a top bar 218. This frame may be depressed against the tension of supporting springs 220 by pressing against a non-metallic heat-insulated finger piece 222 on the slidable frame to bring it to the position shown in Fig. 3, where the type pieces 210 may readily be interchanged. The frame will be held in this lowered position by means of a finger 224 on a latch 226 pivoted in the hanger 14. The finger 224 engages a wear plate 228 attached to the crossbar 218 of the slidable frame and is resiliently held in that position by a spring 230 coiled about a rod 232 in the hanger and engaging a cross flange 234 near the upper portion of said hanger. When the latch 226 is released by pressing against the finger piece 224, for example, then the frame will be raised by the springs 220 assisted by a coiled spring 238 which is attached to the insulated bar 222 and to a pin 240 on the hanger. In case the operator forgets to release this latch before starting the machine, it will be automatically

thrown out by the engagement with the wear plate 228 by a foot 242 secured to the pivoted arm 24 in such a position that it will come into engagement with a surface 244 at the rearwardly projecting end of the latch, it being remembered that the hanger 14 is first moved upwardly to ink the type before it moves downwardly to print the work.

The head 12 is provided with a cross rod 250 which engages the upper surface of the outer ends of the type pieces and serves as an abutment for them. At the same time, the inner ends of the type pieces are provided with curved surfaces 252 adapted to rest at the bottom of the spaces between the projecting teeth of the corresponding type disks. This will bring the character 254 on the type piece in close proximity to the characters 122 at the bottom of the type disks and also to the same level as that of the latter characters and the characters 198 on the name plate 196. The type pieces 210, while readily interchangeable on the crossbar 214 on the sliding frame, fit closely enough thereon so that they are not readily displaced during the re-setting operation and, when the sliding frame is released and the type pieces are brought up against the type disks at one end and the abutment bar 250 at the other end, they are firmly held in operative position. On the front surface 256 of each type piece is engraved a facsimile of the character 254 which is to be printed and this, being in full view of the operator, enables ready selection and interchange of the type pieces. The forward ends of these pieces are notched thereby to provide a small projection 258 which may readily be grasped by tweezers held in the hands of the operator when it is desired to lift a hot type piece from the bar 214 and change it.

For quick operation of the machine, it is necessary that the spare type pieces shall be pre-heated so that it will not be necessary to wait until they have assumed the temperature of the adjacent type disk by conduction. To this end, the machine is provided with a preheater 270 supported on a bracket 272 and comprising a casing within which there is a pancake-shaped electric heating unit surmounted by a metallic type-supporting chase 274. This type chase has side plates 277 and a series of cross ribs 276 corresponding in dimension to the crossbar 214 of the sliding frame so that the type pieces 210 and any spacers 278 that may be employed therewith may be mounted on these ribs and be preheated to a temperature several degrees higher than the sleeve 94. Ledges 280, provided adjacent both sides of the ribs 276, contact with bottom surfaces 282 and the characters 254 on the type pieces and accelerate the transfer of heat to these pieces.

Any desired character on a type disk may be brought into operative position by lifting a corresponding latch-handle 114 and turning the heat-insulated hand wheel 104, this resulting in the rotation of the keyed together sleeves 96 and 94 and the turning by friction of the released type disk. Having selected the proper type pieces 210 and mounted them on the crossbar 214, spacers 278 will be screw clamped to the bar to hold the type pieces in position. The size disk will then be moved to the desired position by oscillations of the handle 126. It will be observed from Fig. 1 that the machine is assembled to include another such oscillatable handle 127 where there is some other type disk, as for match marking, which is

to be set frequently. The work support 10 will be adjusted to a plane exactly parallel to the marking characters on the type disks in their printing position by turning the screw 58 and thereby swinging the supporting arm 56 slightly up and down. Then, as the operator depresses the treadle attached to the treadle rod 36, the type head will be inked from the ribbon 48 and make an impression on work supported on the pad 50 of the work support. The dwell of the printing characters on the work may be increased by screwing up the work support by the hand wheel 60.

Having thus described my invention, what I claim as new and desire to secure by Letters Patent of the United States is:

1. In a marking machine, a marking head, a marking head carrier for moving the marking head in a predetermined path from a fixed outer limit toward a fixed inner limit, power-operated means, a rigid member of predetermined length interconnecting the power-operated means and the marking head carrier arranged to move the carrier in one direction, said member being slidably mounted at one of its points of connection, a spring interposed between the power-operated means and the carrier for moving the carrier in a direction opposite to the movement caused by the rigid member, and means for adjusting the tension of the spring without changing the fixed outer limit of movement of the marking head.

2. In a marking machine, a marking head having heated marking members, a walking beam for moving the marking head in a predetermined path from a fixed outer limit toward a fixed inner limit, power-operated means, a pitman interconnecting the power-operating means and the walking beam for moving the walking beam in one direction, said pitman being slidably mounted at one of its points of connection, means for limiting the sliding movement of the pitman in one direction to fix the outer limit of movement of the marking head, a force transmitting spring interposed between the power-operated means and the walking beam for moving the walking beam in a direction opposite to the movement caused by the pitman, means for adjusting the tension of the spring to vary the force transmitted to the marking head without changing the fixed outer limit of movement of the marking head, and a work-support disposed in the path of movement of the marking head and adjustable toward and away from the fixed outer limit of movement of the marking head to vary the dwell of the heated marking members in contact with a work piece on the work support.

3. In a marking machine, a marking head having heated marking members, a walking beam for moving the marking head in a predetermined path from a fixed outer limit toward a fixed inner limit, power-operated means, blocks pivotally supported, one on the power-operated means and one on the walking beam, a pitman interconnecting said blocks comprising a headed rod connected to one block and slidably mounted on the other block, a spring associated with the rod for holding the last-mentioned block against the head of the rod, screw means for adjusting the tension of the spring without changing the fixed outer limit of travel of the marking head, and a work-support disposed in the path of movement of the marking head and adjustable toward and away from the fixed outer limit of movement of the head to vary the dwell of the heated marking

- members in contact with a work piece on the work-support.
4. In a marking machine, a toothed type disk rotatably mounted in the machine, the ends of the teeth on said disk being provided with printing characters, and a pawl for said disk straddling the periphery thereof and having a portion disposed between adjoining printing characters when in its holding position, said disk being provided with means for lifting the portion of the pawl disposed between adjoining printing characters over the printing characters as relative rotation is produced between the disk and the pawl.
5. In a marking machine, a type disk having printing characters on its periphery, means for supporting said disk for selective rotary movement, a ratchet formed at one side of the disk, a pawl associated with the ratchet, and means on the pawl straddling the periphery of the disk and constructed and arranged to cooperate with the opposite side of the disk to hold the pawl in alinement with the ratchet.
6. In a marking machine, a support, a type disk rotatably mounted on the support and provided with peripheral printing characters, a ratchet associated with one side of the disk and having teeth which are positioned in a predetermined relation to the characters, and a pawl engaging said ratchet, said pawl having a portion which extends across the periphery of the disk and engages the other side thereof, said ratchet being constructed and arranged to lift the pawl radially beyond the peripheral characters thereby to avoid damage to said characters.
7. In a marking machine, a support, a type disk rotatably mounted on the support having peripheral teeth bearing marking characters, a ratchet on one side of the type disk and having teeth associated with the teeth of the disk, a pawl cooperating with the ratchet, a rod on said pawl extending transversely of the disk, and a flange on the rod engaging the other side of the disk.
8. In a marking machine, a head provided with a plurality of toothed type disks having peripheral printing characters, an abutment extending across said type disks, a type supporting frame movably mounted on the head and having a bar substantially parallel to the axis of the type disks and adapted to support individual type pieces, and means for moving said bar to a position where the type pieces are pressed at one end against the type disks and at the other end against the abutment.
9. In a marking machine, a marking head having printing characters mounted thereon, abutments adjacent to said printing characters, and a movably mounted type-piece-supporting bar positioned near the lower part of said head and lying between said abutments, said type piece supporting bar being movable to a position adjacent to said abutments where type pieces positioned on the bar are held against said abutments.
10. In a marking machine, a marking head movable up and down toward and away from the work, said head being provided with marking characters, and means for supporting a row of interchangeable type pieces in marking position on the head comprising a bar of polygonal cross section extending alongside said head near the lower portion thereof, a movable support for said bar slidable heightwise of the head and resilient means for moving said bar toward the head whereby type pieces frictionally positioned on the upper side of said bar when the latter is in depressed position will be raised by said resilient means into contact with the marking head and held in position adjacent to the marking characters thereon.
11. In a marking machine, a marking head movable up and down into and out of contact with the work, said head comprising type disks rotatable about a substantially horizontal axis to provide a row of characters at the bottom of the disks, a carrier for loose type pieces movably positioned on said head and comprising an elongated bar parallel to the axis of the type disks and having a greater heightwise cross-sectional dimension than its corresponding widthwise dimension, means for holding said carrier in depressed position below the head to receive deeply notched type pieces dropped over the bar, and resilient means for moving said carrier toward the head to bring the characters on the type pieces into the plane of the characters at the bottom of the type disks.
12. In a marking machine, a marking head movable up-and-down into and out of contact with the work, said head comprising type disks rotatable about a substantially horizontal axis to provide a row of characters at the bottom of the disks, a carrier for loose type pieces movably positioned on said head and comprising an elongated bar parallel to the axis of the type disks and having a greater height-wise cross-sectional dimension than its corresponding width-wise dimension, means for holding said carrier in depressed position below the head to receive deeply notched type pieces dropped over the bar, and resilient means for moving said carrier toward the head to bring the characters on the type pieces into the plane of the characters at the bottom of the type disks, and an abutment for the upper faces of the type pieces running parallel to the carrier bar and in front of the same.
13. In a marking machine, a marking head comprising a plurality of toothed type disks having printing characters on the ends of the teeth thereof and adapted to be brought into alinement to provide a row of marking characters, a plurality of loose type pieces, and means for supporting these pieces in alinement to provide another row of characters parallel to the selected row on the disks, said means comprising an abutment on the head extending alongside the disks, a movable type-piece-supporting member positioned between the abutment and the type disks, and resilient means for holding said type-piece-supporting member against the type pieces to press one end of each type piece into a recess between the successive teeth of a disk and the other end against the abutment.
14. In a marking machine, a type piece having a printing character on its under side and an end surface facing the operator and provided with a corresponding character visible to the operator, said type piece also having a lip adjacent to the latter character-bearing portion thereby to aid the operator in grasping the type piece.
15. In a marking machine, a marking head having printing members, means for oscillating said head to carry the printing members into contact with a piece of work, a frame movably mounted on the head and adapted to support interchangeable type pieces, spring means for moving said frame to operative position adjacent to the head, a latch for holding the frame in inoperative position with the type pieces below the head, and means operative to release said

latch prior to engagement of the type pieces with the work.

16. In a marking machine, a movable carrier, a type head supported on said carrier for movement toward and away from the work, marking members on the head, a type-piece-supporting member slidably mounted on the head for movement to an inoperative position permitting interchange of the type pieces carried thereby, ¹⁰ silent means for moving the supporting member to operative position in which the type pieces are supported by the head, a latch for holding said member in inoperative position, and means for releasing said latch at the commencement of ¹⁵ the cycle of operation of the machine and before the type pieces are brought into engagement with the work.

17. In a marking machine, a type chase comprising a plurality of upstanding ribs designed ²⁰ to support loose type pieces having notches fitting the ribs, said ribs being mounted in terraced relation, and means for heating the ribs.

18. In a marking machine, a type chase, a plurality of members thereon arranged in terraced relation, each of said members comprising ²⁵ an upstanding rib and a ledge beside the rib, said ledge being adapted to support a portion

of a type piece having a notch to receive the rib, and means for heating said terraced members.

19. In a preheater for use with a marking machine having a bar adapted to support slotted loose type pieces having printing characters thereon, said preheater having heated ledges and adjacent ribs, said ribs being arranged to enter the slots of said type pieces to support them with the printing characters thereon in juxtaposition to said heated ledges. ⁵ ¹⁰

20. In a marking machine comprising a marking head having marking characters positioned thereon in marking position and a bar supporting slotted type pieces with their characters in ¹⁵ the same plane as said marking characters, a type chase for preheating said slotted type pieces, said type chase having ribs shaped similarly to the supporting bar for supporting the slotted type pieces and heated ledges thereon having the ²⁰ same relation to said ribs as the plane of the characters bears to the bar of the machine whereby characters of type pieces placed on the ribs are disposed in juxtaposition to the heated ledges. ²⁵
